UNITED STATES PATENT OFFICE.

FREDERICK SNOW, OF CHICAGO, ILLINOIS, ASSIGNOR TO THE TROY LAUNDRY MACHINERY COMPANY, LIMITED, OF TROY, NEW YORK.

BUTTON-MACHINE.

SPECIFICATION forming part of Letters Patent No. 651,213, dated June 5, 1900.

Application filed October 26, 1899. Serial No. 734,835. (No model.)

To all whom it may concern:

Be it known that I, FREDERICK SNOW, a citizen of the United States, residing at Chicago, in the county of Cook, State of Illinois, have 5 invented certain new and useful Improvements in Button-Machines, of which the following is a specification, reference being had therein to the accompanying drawings.

This invention relates to a machine for 10 making buttons and studs used in collars, cuffs, and shirts, especially by manufacturers of those articles and by laundrymen upon such goods when returned to their patrons.

Among the objects of the invention is to 15 provide a machine that will make buttons by a succession of operations upon a wire of metal or of any other suitable material, so that as the material is fed into the machine buttons are delivered therefrom by a continuous process which is automatic from beginning to end.

Other objects and advantages of the invention will appear in the following description, and the novel features of the invention are 25 particularly pointed out in the appended claims.

Referring to the drawings, Figure 1 is a plan; Fig. 2, a central vertical longitudinal section; Fig. 3, a right side elevation; Fig. 30 4, a left side elevation; Fig. 5, a transverse vertical section on the line 55 of Fig. 1, looking forward, of a machine embodying my invention. Figs. 6 to 11, inclusive, are vertical sections of the immediate button-forming devices in their relative positions assumed in the several progressive steps of making buttons. Figs. 12 and 13 are sectional details of a punch-carrier and means for adjusting its working position. Fig. 14 is a perspective 35 of the button-transferring nippers, with the vertically and longitudinally reciprocating heads carrying said nippers. Fig. 15 is a perspective of devices for moving the nippers rearwardly. Figs. 16 to 21 are details in perspective, elevation, and section of devices for preventing the withdrawal of a wire length or blank from a die at a withdrawal of a punch. Figs. 22 and 23 are a rear side perspective and a partial front side elevation of 40 a wire-cutter and blank-transferrer. Fig.

24 is a perspective of nipper-opening levers and their support. Fig. 25 is a diagrammatic plan of devices for partially ejecting a partly-formed button from a punch or die. Fig. 26 is a side elevation of devices, including an eccentric and a sliding cam, for opening and closing by intermediate connections a pair of split dies. Fig. 27 is a plan of a rock-shaft for raising and lowering the punch or die head. Fig. 28 is a perspective of means 55 for moving the split-die carrier rearwardly away from the upper fixed die. Fig. 29 is a perspective of an arch carrying the nipper-lever-operating cam and a projection for forcing the longitudinally-reciprocating nipper-head forward. Fig. 30 is a perspective of the wire-cutter-reciprocating devices. Fig. 31 is a perspective of the support and guide for the split dies and one of the die-carrying blocks. Fig. 31^a is a detail of a split-die-carrying block.

Like reference characters are applied to like parts in all the figures of the drawings.

Broadly speaking, the operator of a machine embodying my invention first feeds a 75 suitable length of wire; second, cuts it off from the main strand and moves the severed length into alignment with hollow punches opposing each other; third, gages said wire length or blank in said punches with the 80 proper length within and between the punches to form the head, neck, and base of a button; fourth, partially upsets—that is, bulges—the blank at a predetermined point in its length to partly form the base of the button; fifth, 85 completely upsets one end of the blank to form a completed base of the button; sixth, transfers the partly-formed button to a position opposite a head-forming die into which the unformed end of the blank is, seventh, 90 forced, thus completing the button, and, eighth, ejecting it from the die and machine. This operation is automatic and continuous and may be the sole performance of my invention; but to increase the product of my 95 machine I so arrange and time the acts of the successive operating parts that as a first-entered wire length reaches the head-forming die and a complete button is there formed a second-entered wire is having a completed 100

base formed thereon. In this manner the machine is operating upon two blanks at one and the same time.

With this general statement I will now proceed with a more particular description of the construction and operation of the various elements of the machine.

Referring to Figs. 1, 2, 3, and 4 of the drawings, in a main frame 1 there is a crank-shaft 2, carrying a belt wheel or pulley 3 and several eccentrics and cams by which and suitable connections movements in proper time are given to the active parts that work upon the material to form the button.

15 *Feeding.*—On the main shaft 2 is an eccentric 4 of an ordinary wire-feed mechanism comprising a connecting-rod 5 for actuating a rock-arm 6, Fig. 4, carrying a spring pull-pawl 7, acting on a ratchet 8, mounted for 20 rotating the shaft 9, carrying a gear 10, meshing with a gear 11 upon a parallel shaft, these shafts carrying the grooved feed-wheels 12 and 13, Fig. 3. The eccentric 4 has a throw sufficient to move the pawl over such a number 25 of teeth of the ratchet as to rotate the feed-wheels to force into the machine the desired length of wire X to form one button. As before stated, this feeding mechanism is of well-known construction, and any desired 30 mechanism of this character may be employed.

35 *Cutting-off and moving blank.*—Referring to Figs. 1, 3, 5, 6, 22, 23, and 30, I will proceed to describe the devices employed for and their operation when cutting off and moving 40 transversely a blank length from the main wire X. At the right end of the main shaft 2 is a disk 14, adjustably mounted by bolts 37, and wrist-pin 15, on which is connected 45 an adjustable rod 16, pivoted to a sliding plate 17, mounted in a suitable boxing 18. Across-boxing 19, having a guiding-slot 20, is provided on the boxing 18. The plate 17 has a curved slot 21, in which roller-pins 22 and 22^a, Fig. 30, on a cutter-operating rod 23 ride. The lower roller-pin 22^a rides in guiding-slot 20 of the cross-boxing 19. The inner end of rod 23 is secured to the cutter 24, Fig. 5, after it passes through 50 any suitable guide loop or bracket 25. The outer end of rod 23 abuts against an adjusting-screw 26 in a bracket 27, secured to or formed on the main frame 1. A spring 28, extending from a bracket 29 to a pin 30, projecting from rod 23, tends to render the movement of the rod 23 smooth and even. The cutter, Figs. 5, 6, 22, and 23, comprises a body portion 31, having seated in its rear face a tempered-steel cutting-blade 32 and a pivoted 55 wire-holding latch 33, normally closing the entrance to the cutting-blade under the tension of spring 34, mounted on the body 31. The wire-receiving position of the cutter is shown in Figs. 5 and 6 at the left of the vertical central line of the machine, said line being that of the location of the head and base forming dies and punches, being the line

of sections shown in Figs. 7 to 11, inclusive, Fig. 6 being on the wire-receiving vertical line. This being the construction, the operation is 70 as follows: At each revolution of the main shaft the plate 17 is moved forward and backward. In the forward movement the pin-roller riding in the slot 21 is moved toward the frame and causes an inward travel of rod 75 23 and cutter 24. It is understood that a blank length of wire has been fed into the machine through the cutter back of and beneath the latch 33. As the cutter travels transversely of the machine from the wire receiving and guiding tube 35, Figs. 1, 3, and 6, to the central vertical line of the dies and punches it (the cutter) severs the wire and by the spring-pressure of the latch thereon retains and carries the blank to a point in line 80 with the punches and dies. When thus in line, the punches and dies engage the wire, as hereinafter described, and having control of the blank hold it when the cutter is retracted, at which time the spring-pressed 85 latch 33 yields upwardly, freeing the cutter from the blank. The cutter is retracted to a point exactly opposite the guide-tube 35 to receive the next length of wire forced in by the feed at a proper interval of time to allow 90 of the above-described movement of the cutter. Now by means of the set-screw 26 the exact location of the cutting-blade relative to the wire receiving and guiding tube 35 may be accomplished, so that the wire will certainly be fed through the cutter, and by means of the adjustable rod 16 and bolts 37, Fig. 3, the riding of pin-roller 22 upon and for a desired distance along the curve of the slot 21 of plate 17 may be nicely regulated in 105 distance and time, the latter by bolts 37, so as to determine the presentation of the blank exactly in time and in line with the punches and dies. These features for severing and 110 transferring a blank are important to any successful machine and may be employed independent of the remaining structure herein shown and described.

115 *Gaging the wire blank.*—This operation is essential because it requires more of the blank to form the base than the head of the button. Again, it is a problem requiring special solution to upset a slim wire to an extent sufficient to form the comparatively-broad base of the button. Furthermore, the base of the button must not be irregular in contour or thick and heavy, but must be regular and comparatively thin. To produce such a base from comparatively-slim wire requires additional consideration beyond the determination of the proportion of the blank which shall be appropriated for the base, the neck, and the head. Gaging the blank therefore requires accurate action of the machine, while the disposition of the material of the blanks 120 after it is accurately gaged requires some method of operation adapted to the peculiar dimension in cross-section of the material of the blank.

Broadly speaking, the wire is fed farther into the machine than the position that the blank occupies when first operated upon by the punches or hollow dies. After the wire is cut and transferred it occupies such advanced position, and then a movable hollow punch or die advances toward and receives one end of the blank and forces its other end in a direction opposite to that of the feed into a companion punch or die until the wire abuts against an obstruction predetermined in its position to gage the extent of entrance of the wire and the amount of the blank to be appropriated for the head, neck, and base of the button to be made therefrom. Then to accomplish the comparatively very broad upsetting to form the base a preliminary or partial upsetting or bulging of the blank substantially at its mid-length is performed, and subsequently the end projecting beyond the preliminary upset is wholly upset upon and homogeneously united with the preliminary upset to form a practically-solid base. Now taking the wire in the advanced position shown in Fig. 6 and comparing its position in Fig. 7 it will be seen that the blank has been moved to the left by the advancing hollow punch. To facilitate understanding the invention, arrows in the various figures indicate direction of movement, and the terms "punches" and "dies" are used to indicate the work performed by such parts. A die is understood to be a forming part or device, while a punch is a receiving and holding part or device. It will be found that there is one die which is also a punch—that is, said die is hollow and constitutes a die-punch. It is apparent, however, that this compound device might be replaced by a punch and a separate die; but as this would complicate the machine the form shown is employed.

Gaging and upsetting devices.—The part 38, Figs. 7 to 11, inclusive, is a die-punch. In Fig. 7 the cutter 24 is shown in vertical section and in its non-retracted position. There are two fixed and three movable dies and punches, as follows: the lower fixed gaging-punch and preliminary-upsetting die 38, the upper fixed head-forming die 39, the lower base-forming die 40, the middle gaging-punch and preliminary-upsetting die 41, and the base-finishing die 42. The first two are fixed and the last three are movable. The upper die 42 projects farther from its support than the remaining movable dies, and therefore a recess 43 is formed to receive it when advancing in the plane of the recess. The fixed dies are mounted in a fixed part of the frame 1, and the movable dies are mounted on a vertically-reciprocating punch-head 44, carried by a horizontally-reciprocating cross-head 45. The upper movable die 42 is set in a bracket 46, bolted to the head 44, as are dies 40 and 41 in a bracket 47. Proper connections and motion-imparting means hereinafter described give the head, cross-head, and nip-

pers 48 the various motions indicated by the arrows.

The parts described move from their positions shown in Fig. 6 to those shown in Fig. 7. The movable dies have advanced toward the fixed dies, and the wire blank has entered the die-punch 38 until it meets pin 49, and it has also entered punch 41 until it has met an obstruction in the form of a spring-pressed pin 50, the spring 51 bearing against block 52, resting against the punch-head 44 and being a part of slide 132, Fig. 21. The pin 49 extends to a lever 53, Fig. 25, pivoted to the frame 1, (see Fig. 2,) and serves not only as a gaging obstruction, but to partly eject the blank after the base is formed by means of the rod 54 and cam 55. A spring 57 retracts the rod. The partial ejecting of the blank enables the nippers 48 to take the same (see Fig. 11) and transfer it to the upper head-forming dies 39 and 42. After gaging the blank the movable dies continue their advancement, and punch 41 and die-punch 38 slightly upset the blank at about its mid-length, as shown in Fig. 8. In this operation the ejector-pin 49, gaging obstruction 50, and the frictional contact of the dies hold the blank against movement. Die 42 is now in recess 43. The next movement of the die-head is backward and upward, and at this step in the operation care must be taken to prevent the die 41 from drawing the blank from die-punch 38. The provision of means insuring this care is made by devices to be hereinafter described. Another feature to be now observed is that the upward movement of the die and punch head is just sufficient to bring die 40 in exact line with the die-punch 38, so that it may complete the base; also, that the punch-head has already made one advance to gage the blank, so that two horizontally-reciprocating movements of the head are made at each revolution of the main shaft, for a feed of new stock occurs but once during each revolution of said shaft. This double advance of the movable dies is produced by the crank-and-toggle-lever connection of the cross-head 45, as hereinafter described. As head 44 recedes and rises it withdraws punch 41 from the partly-upset blank and brings die 40 opposite die-punch 38, in which the blank remains, and then advancing die 40 completes the upsetting of the blank to form the base. Now the rod 49 partly ejects the blank from die-punch 38, and the nippers 48 now seize the blank and carry it up in front of head-dies 39. In the meantime—that is, after rod or pin 49 has ejected and nippers 48 have removed the blank from die-punch 38—a succeeding blank has been brought opposite said punch 38 and head 44 has been lowered to gage said succeeding blank. In actual work the act of the lower die 40 in completing the base, as just described, is accompanied with the simultaneous act of dies 39 and 42 in forming the head of a pre-

ceding blank; but as an initial blank has been referred to reference is now had to the second or succeeding blank introduced, and for the moment disregarding the operation 5 on said initial blank, letting it rest in position to be headed, (having lowered the head and gaged the succeeding blank, die 42 entering recess 43 below the upper fixed head-forming die 39, and then retracting the head 10 and raising it after the partial upsetting of the second blank to fully upset and form a base on it,) the co-operative parts are in the position shown in Fig. 9. At this time, just before the final upsetting, the nippers, having 15 carried the first blank upward, move to the front and a pair of split dies 141 move against and seize the blank by the neck, after which the nippers open and the punch, or head-finishing die advances and forces the blank 20 into the head-die 39, forming a head of that portion of the blank projecting out beyond the split dies, they being mounted on carriage 164 for movement with the die 42. At the same time and during the same movement 25 of the punch-head the lower die has finally upset the second blank to form the base. A slight countersinking of the head-die 42 (see Fig. 6) serves to put a finishing touch on the previously fully upset base of 30 the button. This function of the movable head die or punch, may or may not be employed as desired.

It now remains to eject the completed button from the machine. Referring to Figs. 2, 35 5, and 14, there will be seen mounted on the front of the nipper-carriage a projection 58, which on the downward movement of the nippers passes directly in line with the finished button as it projects from the upper 40 fixed head-forming die 39, (the split-dies being open,) the frictional contact of the material being sufficient to hold the completed button. The contact of projection 58 knocks the button from the die and down a passage 45 59 (see Fig. 2 and dotted lines in Fig. 5) into a trough 60, Fig. 2, which conduct it into any suitable receptacle. A deflecting plate or trough 61 is located immediately below the projection to deflect the button into the 50 passage 59.

It now remains to describe the devices and connections for giving the dies, punches, and nippers the various motions hereinbefore mentioned, as well as the means for preventing 55 a withdrawal of the blank from the lower fixed die and the double advance and retreat of the punch at each revolution of the main shaft. Fig. 2 shows plainly the connection of the punch-head and cross-head with the 60 main shaft. 62 indicates the cranks on the main shaft, and 63 a connecting-rod which is mounted at its free end on the pivot 64 of the toggle-levers 65 and 66. The toggle-lever 65 is pivoted in a cross-beam 67, adjustably 65 mounted in the frame 1, by means of bolts 68, and a wedge 69 arranged between the cross-bar and frame and adjusted by the bolt 70,

nut 71, and bracket 72. The forward toggle-lever 66 is pivoted to the cross-head 45. The pivot 64 is substantially in the same vertical 70 plane as the center of the main shaft. This arrangement produces two reciprocations of the cross-head during each revolution of the main shaft. Starting with the crank upright, the middle toggle-pivot being at the highest 75 point it reaches above a straight line passing through the three pivots, the crank moving downward to the left, Fig. 2, the toggles approaching said straight line move the cross-head and the punch-head thereon toward the 80 front. The crank continuing to a point below the center of the shaft depresses the toggle below said straight line, drawing the cross-head backward, giving one reciprocation, and the further movement of the crank from the 85 point below the center of the shaft upward to the right raises the middle pivot of the toggles to the said straight line, again forcing the cross-head forward, and the continued movement of the crank to complete a circle 90 raises the middle pivot above a straight line, which again draws the cross-head to the rear, giving a second reciprocation. Taking the parts as shown in Fig. 2, at the first forward movement of the cross-head the head is 95 formed upon the upper blank and the final upsetting takes place on the lower blank to form its base. (See Fig. 10.) At the first backward movement of the cross-head the parts assume the positions shown in Fig. 7. 100 At the second forward movement the preliminary upsetting takes place, Fig. 8, and at the second backward movement the punch-head is raised, so that at the first forward movement of the next revolution the base and 105 head forming dies are brought again into action.

Raising and lowering the punch-head.—Upon the inner face of disk 14 is a cam-groove 73 (see dotted lines, Fig. 3) for reciprocating a slide 74, riding in gibbs 75 on the frame 1. An adjustable connecting-rod 76 extends from the slide to a rock-arm 77, having a slot 78, in which the end of the connecting-rod may be secured at various points 110 to determine the extent of movement given by the slide to the rock-arm, and thus the extreme points of rest of the punches and dies are regulated coarsely by the slot connection and to a finer degree by the adjustment on 115 the connecting-rod. The rock-arm 77 is rigidly secured on a shaft 79, mounted on and extending transversely under the frame 1, and having a central bifurcated rock-arm 80, (see Fig. 27,) embracing a rotatable block 81, 120 adapted to receive a rigid pin 82, projecting from the lower end of the punch-head 44. The cam 73 is so timed with relation to the crank 62 as to effect the raising and lowering of the punch-head agreeably with the reciprocations 125 of the cross-head in order to secure the co-operation of these parts and the fixed dies, as hereinbefore described.

Nipper-operating devices.—On the main

shaft at the left of crank 62 is a disk 83, Figs. 1 and 4, having a face cam-groove 84, for operating a slide 85, which is connected by a link 57 with one arm of a short rock-shaft 86, 5 the other arm 87 of which is connected by an adjustable rod 88 with one arm 89 of a similar rock-shaft 90 by a bolt-and-slot structure 91, secured in adjustment by a set-screw 92, while the other arm 93 of the rock-shaft 90 10 is connected by a rod 94 with the vertically-reciprocative nipper-carriage 95. Duplicating the rock-shafts 86 and 90 increases the extent of movement in the rod 94, and by interposing the adjusting-rod 88 the finer regulation 15 of the time of movement of the nipper-carriage is accomplished, the bolt-and-slot structure 91 giving the coarser regulations.

Referring now to Fig. 14, 96 is a standard bolted upon the frame by means of the flange 97, and upon this standard the nipper-carriage 95 is mounted to move up and down when operated by the rod 94. Upon the inner face of the carriage there is slidingly mounted one leg 98 of a bracket, the other leg 99 of which constitutes a holder for the nippers 48. This holder is in the form of gibbs embracing a lateral arm 100, projecting from a hollow head 101, in which the nipper-jaws are pivoted, as at 102. Springs 103, secured to the head, project against each jaw to normally press them together. Each jaw has below its pivot a rearward projection 104. The leg 98 ends in an incline 105, terminating in a downwardly-projecting lip 106. This lip is adapted to be caught by a lip 107 on a sliding rod 108, mounted in a bearing 109, secured upon the frame 1. (See Fig. 15.) The rod is retracted by a spring 110 and is drawn rearwardly by a lever 111, pivoted to a bracket 112, when struck by a cam 113 on the face of disk 83, mounted on the main shaft. It will be seen that connection of the lips 106 and 107 can take place only when the nippers are at the lowest point of their travel, and therefore the purpose of said connection and rearward movement of the rod 108 is to withdraw the blank from the lower die 38 after the base is formed thereon, as hereinbefore described.

is formed thereon, as heretofore described.

The nippers are opened by means of the levers 114 and 115, pivoted at 116 in a box 117, (see Fig. 24,) which is mounted on the punch-head (see Fig. 1) by means of a bolt passing through the box and into the head, as shown. The projecting ends of the levers are provided with antifriction - rollers and are normally drawn toward each other at their front ends by a spring 118. The device for operating the levers 114 and 115 consists of an arch 119, carrying a bifurcated plate 120, Figs. 1 and 29, said bracket being mounted upon the frame in the vertical path of the levers 114 and 115, so that in a forward movement of the punch-head at its upper position the enlargement 121 of the plate act as cams upon the rear ends of the levers and cause their front ends to open the nippers. They are closed by the springs 103. The arch 119 also sup-

ports a bracket 122, provided with an anti-friction-roller 123, which bracket is in the path of the incline 105 of the leg 98 of the nipper-carrying bracket, so that as the nipper-carriage rises and falls the nippers are changed from one vertical plane to another to be in position to allow die 42 to advance when the nippers are opened by the plate 120 and to be spring-pressed to a closed position when the arms 114 and 115 escape from said plate. Incline 105 and bracket 122 (see Fig. 4) force the nippers forward when they rise after the rod 108 has drawn them rearwardly at the time the nippers are down. 70 75 80

Prevention of accidental withdrawal of blank from die-punch 38.—It has been hereinbefore mentioned that great care must be exercised at that step in the progress of the machine wherein the punch-head retreats and rises to substitute the die 40 for the punch 41 in the position to operate upon the blank immediately after the preliminary upsetting has been performed thereon. The position of the parts referred to is clearly shown in Fig. 8. The curved arrows indicate the inward and upward movement of the punch-head. This movement being not directly in line with the blank has a tendency to withdraw the blank from die-punch 38, and the description will be now given of the devices employed to prevent such withdrawal. It will be conceded that if any device be provided which shall prevent sufficient frictional contact of the blank in punch 41 as the punch-head retreats the liability to withdraw the blank will be overcome.

Reference will now be made to Figs. 6 and 16 to 21, inclusive. Referring to Figs. 6 and 16, 50 is the obstruction or pin in die 41, which is mounted in the bracket 47, which in turn is secured to the punch-head by a rib-and-bolt construction, which permits of the lateral adjustment of the bracket 47 on the head. To be more specific as to the particular means employed in this instance, the bracket 47 is provided with a rib 125, which rides in a groove formed in the punch-head 44 and transversely thereon, while a bolt 126 projects from the punch-head, passing through a sleeve 127, which is in a slot 128, formed in a projection upon the bracket, and set-screws 129 retain the bracket in any lateral adjustment thereof, which is exercised for the purpose of centering the punches. A set-screw 130 is provided for each punch in order that it may be securely retained in the bracket. The pin 50 is backed by a spring 51, which is cushioned against a block 52, formed as or on a plate 132 and which is adapted to move within the body of the bracket and is provided with a projection 133, which passes through a slot in the wall of the bracket. This projection 133 has a beveled lower surface. A projection 134 is provided on the bracket below the projection 133 and terminates in a V-point or double-beveled end 135. Now recalling the fact that the bracket advances and

retracts with the punch and cross heads it will be seen that if the obstruction is put into the path of the lug or projection 133 as the bracket recedes the plate 132 will be held 5 against retraction and the spring 51 will be compressed and exert a pressure on the pin 50, and this in turn will exert force against the end of the blank in the punch 41, and thus serve to force the blank out of the punch 10 before the punch and bracket will have begun to rise. A spindle 50^a may (see Fig. 21) or may not (see Figs. 6, 7, and 8) be used, projecting from the pin 50, so that if the tension of spring 51 be not sufficient to force the blank 15 out the spindle will be struck by the plate 52, and thus produce the desired result. The application of the obstruction to the sliding plate projection 133 should be held but for a brief period of time, so that the retractive 20 and upward movement of the punch-head may take place in its proper time.

The device which is employed to cause the plate 132 to slide and the pin to eject the blank from the punch is a trip 136. This trip 25 is mounted on a slide 140 in ways 137, formed in the bracket 138, which projects from the frame in such a manner that the trip 136 shall be in the path of the projection 133 of the sliding plate 132, while a lower V-shaped trip 30 139, carried by the same slide 140 which carries the trip 136, is in the path of the V-point 135 of the projection 134 of the bracket 47.

Figs. 18, 19, and 20 illustrate the passage 35 of the bracket 47 and the action of the trip on the projection 133. The arrows indicate the movements of the parts. A spring 131 tends to keep the projection 136 elevated, while the inclined upper surface of the trip 136, riding in contact with the projection 133, 40 has the effect of depressing the trip and the slide. In Fig. 18 the punch-block and projection 133 are traveling to the right while the point 135 is riding on one of the inclined faces of the block 139. This depresses slide 45 140 and projection 136 so that the projection 133 passes without being operated to slide the plate 132. This operation takes place in an advance of the punch-head. In Fig. 19 the curved arrows indicate a retractive movement 50 of the punch-head and bracket 47, wherein the V-point 135 is riding an opposite incline of the projection 139, and thus raises the slide 140 and trip 136 upwardly into the path of the projection 133, so that the plate 55 132 is caused to compress the spring and force the pin 50 against the blank, thereby clearing it from the punch 41. As the point 135 reaches and passes over the apex of the projection 139 the trip 136 is depressed by the spring 131, so 60 as to allow the passage of the projection 133 in the further outward and subsequent upward movement of the bracket 47 and of the punch-head. In this way a momentary forcing of the blank out of the punch is accomplished. The plate 132 and its projection 133 65 may be termed an "ejector-operating device," and the coacting trip 136 and its ad-

junctions may be termed an "ejector-actuating device."

Split dies.—A reference to Figs. 5 to 11, inclusive, will show the presence of split dies 141 in various positions with relation to the head-die 39. The split dies and the head-die are mounted in a carriage 146, and it will be noted that the carriage also is shown in varied positions with relation to the frame of the machine to which the lower die-punch 38 is fixedly secured. In Fig. 6 while the wire is being fed into the machine the die-carriage 146 is in a retracted position. In Fig. 7 said carriage is thrown forward during the operation of gaging the blank and while the preliminary upsetting and also while the final upsetting of the base is accomplished. In the act of the final upsetting (see Fig. 10) it will be noted that the carriage 146 has retracted a distance and that the die 42 is bearing against the completed base of the button. The distance that the carriage has been retracted is about equal to the extent of projection of the die 42 beyond that of the dies 40 and 41. This fact is clearly shown in comparing Fig. 8 with Fig. 10. The reciprocation of the carriage 146 is produced by a cam 147 on disk 14, Figs. 1 and 28, which acts upon a push-rod 148, bearing against an arm 149 of a rock-shaft mounted in a bracket 150, projecting from the frame, the other arm 151 of which rock-shaft acts upon an arm 152, carrying a bolt 153, which bears against a lug 154 on the carriage 146. The arm 152 is rigidly secured to a rock-shaft 155 in bearings 142, Fig. 1, bearing a companion arm 156, that acts upon the carriage by similar means to that mounted in arm 152. Adjusting-screws 157 enable an accurate determination of the operation of the rock-shaft and rod 148. Upon the carriage 146 are the bearings 158 for a rock-shaft 159, (see Figs. 1, 2, and 5,) the arms 160 of which are connected by links to toggles 161, a pair of which is provided for each half of the split die 141. A key 162 and bolt 163 serve to adjustably secure the die *per se* in its carrier or block 164. The necessary motion of the rock-shaft to open and close the split dies is communicated thereto by a cam-bar 164^a, having a surface cam 165 thereon upon which a T-head 166, rigidly secured to the rock-shaft, rides. These parts are illustrated in Figs. 1, 3, 5, and 26. An eccentric 167, mounted on the main shaft, has its rod 168 extended in a position parallel with the cam-bar 164, and said rod is provided with a pin 169, which passes through said cam-bar, 175 whereby the same is reciprocated, and the undulating surface of the cam 165 causes the T-head to oscillate, and thus acts upon the rock-shaft to raise and lower the toggles 161, and thus open and close the split dies 141. 180 These parts are timed to perform these operations in proper relation to the remaining elements of the machine.

The split-die carriage 146 (see Fig. 31) is

provided with suitable seats 170 for the pivotal support of the outer ends of the outer toggles 161 and a suitable track 171 for the die-block 164 to travel upon, which block is 5 provided with a pivotal bearing for the inner toggle, as clearly shown in Fig. 5. A grooved way 172 is provided for the rib 173, projecting from the rear of each die-block 164. Slots 174 are provided in the die-carriage for the reception of travel-limiting pins 175, Fig. 1.

Upper head-forming punch.—While any desired description of punches and dies and carriers therefor may be employed, in an embodiment of the invention in Figs. 12 and 13 are shown the details of construction, mounting, and adjustment of the upper head-die holder, in which 176 is the part having the recess 177 for receiving the die proper. The 15 part or holder 176 is seated in a recess 178, formed in the face of a block 179, mounted on and embracing a projection 134^a on block 184, through which the bolt-receiving opening 180 extends, while the bolt 181 therein is 20 screw-threaded, as shown, into the holder 176, thereby firmly retaining the holder against the recessed block and, if desired, also against the end wall of the projection 184^a of block 184. An adjusting-screw 182 serves for determining 25 the position of the holder in the recess vertically. Within the main or foundation block 184^b there is a recess 183, in which is located block 184, which is a secondary or spacing block. A recess 185 in said 30 block receives a pin 186 on the main or foundation block 184^b. The rear edge of the spacing-block 184 is inclined with relation to its face, and between it and the vertical rear wall of the recess 183 is inserted an adjusting- 35 wedge 187, the screw 188 serving to retain said wedge in an adjusted position. The purpose of the bolt 181 is to maintain in rigid condition the holder 176 after it is once adjusted by the devices described. The wedge 40 187 is to provide fine longitudinal adjustment of the holder. Fig. 13 is a section on the line 13-13 of Fig. 12, and it shows laterally-perforated flanges 189, through which bolts 190, Fig. 1, pass into the frame 1, upon 45 which the upper head-die is mounted.

To adjust the feed-rollers 12 and 13 to feed wires of various sizes, the shaft of the upper roll 12 is mounted near one end in a bearing supported on pivots 191, Fig. 1, and near the 50 other end by a bearing having an arm 192, which projects through bracket 193, projecting from frame 1. (See Fig. 2.) A screw 194 passes through the bracket and bears upon the arm 192, so as to regulate the pressure 55 of feed-wheel 12 upon the wire. By the same screw the feed-wheels are adapted to wires of varied sizes. 195, Figs. 1 and 3, is a wedge controlled by the bolt 196, projecting from the end of the frame and passing 60 through a flange 197, formed at the end of the wedge and provided with a set-nut 198 in order to maintain the wedge in an adjusted

position. This wedge is inserted between the frame 1 and the split-die carriage 146.

The description of the details of construction hereinbefore appearing are merely of one of many forms which may be employed, these matters being within the skill of the mechanical constructor of a machine embodying the invention. It is therefore apparent that to these features the invention is not limited.

What is claimed as new is—

1. In a machine for making buttons from material in wire form, forming-dies, wire-feeding devices, cutting mechanism, and means independent of the dies for gaging the severed blank; substantially as specified. 80
2. In a machine of the character described, wire-feeding mechanism, cutting mechanism, and means mounted on the cutter for transferring a blank after it is severed from the main wire; substantially as specified. 85
3. In a machine of the character described, feeding mechanism combined with cutting mechanism adapted to hold and transfer a severed blank from the position where it is severed to a position to be operated upon by other devices; substantially as specified. 90
4. In a machine of the character described, the combination of feeding mechanism, a single device constituting a combined cutting and transferring mechanism, and gaging mechanism; substantially as specified. 95
5. The combination of wire-feeding mechanism, cutting and transferring mechanism, head and base forming dies and gaging mechanism independent of said dies; substantially as specified. 100
6. The combination of feeding mechanism and cutting mechanism provided with blank-retaining devices; substantially as specified. 105
7. The combination with feeding mechanism, of movable cutting mechanism provided with a latch operating to retain a severed blank, whereby the severed blank is carried from one position to another; substantially as specified. 110
8. The combination with feeding mechanism of cutting mechanism provided with spring-pressed pivoted latch; substantially as specified. 115
9. The combination with feeding mechanism, cutting mechanism provided with a blank-retaining device, and means for moving the cutting mechanism beyond the point necessary for severing the blank; substantially as specified. 120
10. The combination of feeding mechanism, cutting mechanism provided with a blank-retaining device means for reciprocating said cutting mechanism, and gaging means arranged a distance from the point of severance by the cutting mechanism; substantially as specified. 125
11. The combination of feeding devices, cutting and transferring devices, and gaging devices arranged adjacent to the point of severance of a blank by the cutting devices, and 130

- means for ejecting the blank lengthwise from the gaging devices; substantially as specified.
12. In a machine of the character described, 5 hollow gaging devices having obstructions for determining the position of a blank therein, and means for ejecting the blank lengthwise therefrom; substantially as specified.
13. In a machine of the character described, 10 hollow gaging devices having automatically-movable obstructions for determining the position of a blank therein; substantially as specified.
14. In a machine of the character described, 15 gaging devices having each a movable obstruction, one of which is adapted to eject a blank therefrom; substantially as specified.
15. The combination in gaging devices, of 20 means for locating a blank in one member thereof disproportionately to the amount of material to be consumed in successive operations thereon, and obstructions to the entrance of the blank into said devices, one of which obstructions is spring-pressed, and of 25 means for moving one of said gaging devices toward the other to proportionally arrange the blank; substantially as specified.
16. The combination of gaging devices capable of relative movement toward each other, 30 the one having an obstruction yieldingly mounted therein, and the other having therein an obstruction relatively, fixedly, mounted; substantially as specified.
17. The combination with gaging devices, 35 one of which has a yielding obstruction and the other a relatively-fixed obstruction, of means for moving the relatively-fixed obstruction to eject a blank therefrom; substantially as specified.
18. In a machine of the character described, 40 feeding mechanism, combined gaging and preliminary-upsetting mechanism and final-upsetting mechanism acting on the preliminarily-upset portion; substantially as specified.
19. In a machine of the character described, 45 feeding mechanism, severing mechanism, preliminary-upsetting mechanism and final-upsetting mechanism acting on the preliminarily-upset portion; substantially as specified.
20. The combination of a die and of gaging devices, one of which operates as a die and means for bringing said devices and dies together to form a preliminary upsetting of material; substantially as specified.
21. In a machine of the character described, 55 the combination of a relatively-fixed preliminary-upsetting die, with relatively-movable, preliminary upsetting and final upsetting dies, and means for bringing the latter dies successively into operative position with the former; substantially as specified.
22. The combination with a preliminary 60 fixed upsetting-die, of a movable preliminary-upsetting die and a movable final-upsetting die, a fixed heading-die and a movable heading-die, and means for bringing the preliminary and final upsetting dies successively into a single operative position; substantially as specified.
23. The combination of preliminary-upsetting dies, a final-upsetting die, means for partially ejecting a blank from one of the first-mentioned dies, and means for transferring the partially-ejected blank to the head-forming dies; substantially as specified.
24. The combination of a heading-die, a base-forming die, means for partly ejecting a blank from the base-forming die, and nippers constructed and arranged to withdraw the blank from the base-forming die and transfer it to a position to be operated upon by the heading-die; substantially as specified.
25. The combination of a base-forming die, 85 blank-transferring devices, a heading-die, a movable split die, and a movable base-finishing die, and means for moving the latter toward the split and head-forming dies; substantially as specified.
26. The combination with a heading-die, 90 split neck and bracing die, a base-finishing die, and means for moving the latter and the split die toward the head-die; substantially as specified.
27. The combination with a fixed heading-die and a fixed base-forming die, of base and head finishing dies mounted for vertical and horizontal reciprocation with relation to said fixed dies; substantially as specified.
28. The combination of a relatively-fixed 100 heading and a gaging and base-forming die, with a head-finishing die and base-forming die and a gaging-punch, the three latter being mounted for vertical and horizontal movement with relation to the fixed dies; substantially as specified.
29. The combination with a relatively-fixed heading-die and relatively-fixed gaging-punch and base-forming die, with gripping mechanism and with a head-finishing die, a 110 gaging-punch and a base-finishing die, the three latter being mounted for vertical and horizontal reciprocation, the parts being timed in their successive operations; substantially as specified.
30. The combination of a fixed heading-die, 115 a co-operating base-finishing die, and nippers provided with a button-ejecting projection, and means for reciprocating the nippers for ejecting the button; substantially as specified.
31. The combination with base and head forming dies, of nippers constructed, arranged and timed to transfer a blank from the former to the latter between their successive operations; substantially as specified.
32. The combination with blank-transferring nippers, of split dies arranged and operated to support and move with a blank after the nippers are released therefrom; substantially as specified.
33. The combination with a die-holder, a recessed block for receiving the same and an adjusting-bolt passing through the block into

the holder, a foundation-block and a binding-bolt for securing the parts in an adjusted position; substantially as specified.

34. The combination of a foundation-block

5 as 184^b having a recess therein, a pin projecting into the recess, an incline-faced secondary block having an aperture to receive the said pin and arranged within the recess, an interposed adjustably-secured wedge, a die-holder receiving-block secured to the secondary block and having an adjusting-screw, and a die-holder threaded to receive said screw and a binding-bolt passing through the foundation-block, the secondary block and

15 into said holder; substantially as specified.

35. The combination with a heading-die, of a split neck-embracing die, and toggles for reciprocating each part of said split die; substantially as specified.

20 36. The combination with a heading-die, a split neck-embracing die, toggles for opening and closing said die, a rock-shaft for operating said toggles, having a T-head, and a reciprocating cam-bar for operating the rock-shaft; substantially as specified.

25 37. The combination of a shaft, an eccentric mounted thereon having its rod pivotally connected with a reciprocating cam-bar, a rock-shaft having a T-head arranged to oscillate upon the cam of the bar; substantially as specified.

30 38. The combination with blank-gaging devices, one of which is an ejector device, a pivoted lever contacting with said ejector device at one end, a shaft and a cam mounted thereon, and an interposed rod with one end arranged in the path of the cam and the other end arranged to contact with said lever; substantially as specified.

40 39. The combination with a stationary heading-die, and a split die mounted in a movable carriage, of a base-finishing die arranged to coöperate with the heading-die and to move the split die and its carriage in one direction; substantially as specified.

45 40. The combination with a die-supporting carriage, of a primary rock-shaft mounted upon a fixed part of the framework and having arms adapted to abut against the carriage, a secondary rock-shaft adapted to bear against one of the arms of the primary rock-shaft, a rod adapted to operate the secondary rock-shaft, and a cam mounted upon a rotating shaft adapted to reciprocate the rod to move said carriage in one direction; substantially as specified.

50 41. The combination of a main shaft and reciprocating punch and die-head, connections for conveying motion to the same from

60 said shaft, a die-supporting carriage movable in one direction by a die carried by the punch-head and in the opposite direction by connecting devices extending from said carriage to the main shaft; substantially as specified.

65 42. The combination of a reciprocative punch-head mounted upon a reciprocative cross-head, a main shaft, connections between

the shaft and the cross-head, and separated connections between the shaft and reciprocative punch-head giving movement thereto; substantially as specified.

43. The combination with a crank-shaft, of a connecting-rod and toggle-levers having a movement extending both sides of their straight-line position, one of which is pivoted to a relatively-fixed part and the other to a cross-head, and a reciprocative die or punch-head mounted on the cross-head, and means for reciprocating the punch-head; substantially as specified.

44. The combination with a crank-shaft and connecting-rod, of a cross-head carrying dies or punches and toggle-levers, the middle pivot of which is connected with the rod to straighten said rods at the quarter-turn at each side of the dead-level of the crank-shaft, whereby a double reciprocation of the punches or dies is produced; substantially as specified.

45. The combination of a hollow die, an ejecting-pin, a spring bearing against said pin, and a slideable plate against which one end of said spring bears, and means for sliding said plate; substantially as specified.

46. A hollow reciprocative die having a spring-pressed ejecting-pin and a slideable plate combined with a relatively-fixed device located in the path of said plate; substantially as specified.

47. A hollow reciprocative die having a blank-ejecting device combined with an ejector-operating device, and means for momentarily causing the latter device to act during a primary movement of said die; substantially as specified.

48. A hollow reciprocative die having an ejector combined with an ejector-actuating device mounted for movement at an angle to that of the die; substantially as specified.

49. A hollow reciprocative die having an ejector combined with an ejector-actuating device having means for reciprocating it into and out of the path of the ejector-operating device; substantially as specified.

50. A hollow reciprocative die having an ejector combined with an ejector-actuating device in the form of a yieldingly-supported trip; substantially as specified.

51. An ejector-actuating device comprising a reciprocative bar having a trip, a double-beveled projection and a supporting-spring, combined with a means for reciprocating said bar by contact with said projection; substantially as specified.

52. A hollow die or punch having an ejector mounted therein, means for reciprocating the ejector adapted to reciprocate in and to project from a block supporting the die, means for reciprocating the block, and a fixed bracket carrying a slide in the path of the projection of the ejector-operating means, said slide being provided with a trip and with a double-beveled projection, and means secured to the die-block for operating said projection on the said slide; substantially as specified.

53. An ejector-operating device comprising a slide having a trip and a beveled projection and a spring for moving the slide in one direction, in combination with a reciprocative device moving in the plane of the projection on the slide; substantially as specified.

54. The combination with a die or punch having an ejector, means for operating the same and a trip mounted for movements which allow the passage of the punch and ejector mechanism without an operation of the latter in the movement of the punch in one direction and which actuate the ejector mechanism in the movement of the punch in an opposite direction; substantially as specified.

55. In a machine of the character described, nippers mounted for vertical and horizontal reciprocation; substantially as specified.

56. In a machine of the character described, and in combination with a series of dies, nippers mounted for a continuous successive horizontal and vertical movement extending from one die to another of the series; substantially as specified.

57. In a machine of the character described, nippers mounted for horizontal and vertical movements, in combination with a stationary cam arranged in the path of the nippers and operating to open the same during their horizontal movement; substantially as specified.

58. Nippers mounted for horizontal and vertical movement and means for giving the nippers a horizontal movement at the lowest point of their vertical movement; substantially as specified.

59. In a machine of the character described, nippers adapted for horizontal movement, a sliding bar resting normally in the path of the nipper-supporting devices, and a rotative cam and intermediate connections for reciprocating the bar to move the nippers in one direction; substantially as specified.

60. Nippers mounted for vertical and horizontal movements and having a supporting device terminating in an incline in combination with a bracket arranged in the vertical path of the nipper-support and serving to move said support and the nippers horizontally; substantially as specified.

61. Nippers having a horizontally-moving support mounted on a vertically-moving slide or support, the former terminating in an incline and a depending lip in combination with a bracket for operation upon the incline to move the nipper-support in one direction and with a slidable bar adapted to contact with the lip, and means for reciprocating the bar to move the nipper and its support in an opposite direction; substantially as specified.

62. The combination with a series of dies, of nippers mounted for movement along the series and provided with an ejector; substantially as specified.

63. The combination with a die, of an ejector and a deflector mounted for reciprocation in front of the die; substantially as specified.

64. The combination with nippers mounted for movement along a series of dies and provided with an ejector and a deflector for removing a blank from a die and guiding the direction of the blank when removed; substantially as specified.

65. In a machine of the character described, feed mechanism, a series of dies relatively fixed, and a series of punches and dies movable with relation to the fixed dies, means for transferring a blank from one die to another, and means for bringing the movable dies into operation simultaneously upon two blanks; substantially as specified.

66. In a machine of the character described, a series of fixed dies, a series of dies mounted for horizontal and vertical movements in combination with toggle-levers, a crank-shaft, and a connecting-rod united with the toggle-levers at a point below the center of the crank-shaft, whereby a double reciprocation of the mounting of the die is produced at each revolution of the crank; substantially as specified.

67. In a machine of the character described, a crank-shaft, a connecting-rod extending therefrom to the middle pivot of toggle-levers, a cross-head secured to one of said levers, and an adjustably-mounted wedge interposed between the framework and the part to which the other toggle is pivoted; substantially as specified.

68. In a machine of the character described, a pair of relatively-fixed dies, a set of three movable dies or punches, the upper one of which projects to a greater distance than the remaining two of the three, and a framework having a recess for receiving the upper die of the three when the middle die of the three is co-operating with the lower fixed die; substantially as specified.

69. The combination of a heading-die, and die-punch, each of which is relatively fixed, a base-forming die, a gaging-die and a base-finishing die all mounted for movement in vertical and horizontal directions; substantially as specified.

70. In a machine of the character described, feeding mechanism adapted and operating to feed the wire into the machine beyond the point at which a severed blank is operated upon, and means for retracting said wire to the point of operation thereon; substantially as specified.

In testimony whereof I affix my signature in presence of two witnesses.

FREDERICK SNOW.
